UNITED STATES PATENT OFFICE

JOSEPH GYR AND OTTO KAISER, OF BASEL, SWITZERLAND, ASSIGNEES TO THE FIRM
SOCIETY OF CHEMICAL INDUSTRY IN BASEL, OF BASEL, SWITZERLAND

AZO-DYESTUFFS AND PROCESS OF MAKING SAME

No Drawing. Application filed October 16, 1928, Serial No. 312,928, and in Switzerland October 22, 1927.

The present invention relates to the manufacture of new direct dyeing azo-dyestuffs. It comprises the process of making these dyestuffs, the dyestuffs themselves, and the material that has been dyed with the new products.

In the U. S. specifications Nos. 1,625,530, 1,625,531, 1,625,532, 1,625,533 and 1,667,312 intermediate products and azo-dyestuffs are described which are characterized by the presence of a cyanuric ring. This fundamental invention has also been described in a number of foreign specifications, thus inter alia in British specifications 221,843 and 209,723, French specifications 572,715 and 576,725, and German specification 436,179. The dyestuffs are mostly cotton dyestuffs which are distinguished for their purity of tint, their dyeing capacity and the fastness to light of their dyeings.

According to the present invention new direct dyeing azo-dyestuffs, which may be characterized by dyeing properties essentially better than those of otherwise comparable dyestuffs, are made by introducing the thiazole ring into dyestuffs of the kind described in the said specifications, the introduction occurring either into the diazo component or into the coupling component or into both components.

These new direct dyeing dyestuffs may be made by condensing a cyanuric halide with such components as contain at least one hydrogen atom which can react with a cyanuric halide, at least one of such compounds containing at least one group adapted for azo-dyestuff formation, or a residue capable of transformation into such a group, or an azo-chromophor, and at least one of such compounds containing at least one thiazole ring. The products thus obtained, particularly when they contain no azo-chromophor, may be converted into azo-dyestuffs, if necessary after transferring the aforesaid residue into a group adapted for azo-dyestuff formation, either by diazotization and coupling with a coupling component, or by coupling with any desired diazo-compound. Such dyestuffs may also be obtained by coupling a diazo-body with a coupling compound if these com-

ponents be so selected that the one contains at least one thiazole ring and the other at least one cyanuric ring.

The dyestuff thus made, as expressly stated in the aforesaid specifications, can be subjected to a further treatment, such as further coupling, diazotizing and further coupling, treatment with metal salts either in substance or on the fibre, reduction, condensation, acidylation (including treatment with phosgene), alkylation, aralkylation, arylation or the like. They can also, owing to the good affinity of the respective intermediate products, be completely produced on the fibre.

The new dyestuffs form powders more or less intensively colored, dissolving in water to solutions of all colors of the spectrum and of those which are obtained by combination of the said colors, and dyeing the textile fibre from cellulose or regenerated cellulose similar tints.

The invention permits the production of a very large number of intermediate products and dyestuffs. In the following examples, therefore, only some single members of the principal types of the new products can be adduced for the purpose of indicating the scope of the invention, and it is obvious that the same embraces everything which results by interpolation and combination of the products described both among themselves and with the products of the aforesaid specifications.

In the examples the parts are by weight:—

Example 1

A fine suspension of 18.5 parts of cyanuric chloride in ice water is mixed with a neutral solution of 31.9 parts of 1:8-aminonaphthol-3:6-disulfonic acid and the mixture is stirred for 1-1½ hours at 0° C. During this time there is run in gradually a solution of 5.3 parts of sodium carbonate. There is then added a neutral solution of 32 parts of dehydrothiitoluidinesulfonic acid, the temperature is raised to 40° C. and in the course of 1½ hours a solution of 5.3 parts of sodium carbonate is allowed to flow in. From the

yellow colored solution, after further stirring for 1 hour, there can be separated by salting out the secondary condensation product from molecule cyanuric chloride, 1 molecule 1:8-aminonaphthol-3:6-disulfonic acid and 1 molecule dehydrothiotoluidine-sulfonic acid; when filtered and dried it is a pale yellow powder.

The formula of the new intermediate product is very probably the following:

35 By adding to the above described aqueous solution of the secondary condensation product 9.3 parts of aniline and heating for 1½ hours at 80° C., there is formed the tertiary condensation product from 1 molecule cyanuric chloride, 1 molecule 1:8-aminonaphthol-3:6-disulfonic acid, 1 molecule dehydrothiotoluidinesulfonic acid and 1 molecule aniline; this may be salted out and isolated. It forms a pale yellow powder.

45 The same product is obtained when the three components are caused to act on the cyanuric chloride in another order.

50 Both the secondary and tertiary condensation products are nearly colorless in alkaline solution but on acidification become yellow. They show pronounced substantive character in that they are adsorbed by cotton without development of color in a feebly alkaline bath of Glauber's salt and can be developed, 55 after rinsing, with various diazo-solutions to produce powerful dyeings.

Example 2

18.5 parts of cyanuric chloride finely suspended in icewater are mixed with a neutral solution of 18.8 parts of 1:4-phenylenediamine-3-sulfonic acid and the mixture is stirred at 0-5° C. In the course of 1½ hours a solution of 5.3 parts of sodium carbonate are allowed to flow in. To the slightly slimy condensation mass there is then added a neutral solution of 32 parts of dehydrothiotoluidinesulfonic acid and the whole is heated to 40° C. Within one hour a further solution of 5.3 parts of sodium carbonate is run in, the temperature is kept at 40° C. for some time and the secondary condensation product formed from 1 molecule cyanuric chloride, 1 molecule 1:4-phenylenediaminesulfonic acid and 1 molecule dehydrothiotoluidinesulfonic acid, corresponding very probably with the formula

is caused to separate by salting out or by acidification. In the form of its sodium salt it is a nearly colorless powder; the free acid is yellow. The product has a substantive character; it is adsorbed colorless by cotton in a feebly alkaline bath of Glauber's salt and after the fibre has been rinsed the adsorbed substance may be developed to strong dyeings by diazotizing and coupling with the most various azo-components.

This secondary condensation product may further be condensed to a tertiary product, for instance by adding to the solution described above 9.3 parts of aniline and heating for about 2 hours at 80° C., whereby there is formed the tertiary condensation product from 1 molecule cyanuric chloride, 1 molecule 1:4-phenylenediamine-3-sulfonic acid, 1 molecule dehydrothiotoluidinesulfonic acid and 1 molecule aniline, which has properties similar to those of the above secondary product and corresponds very probably with the formula

The product can also be obtained by causing the components to act on the cyanuric chloride in another order, for instance the dehydrothiotoluidinesulfonic acid may be condensed in the first place.

Isomeric products having similar properties are obtained by substituting its sulfonic acids for the aniline and monoacetyl-para-phenylenediamine or para-nitraniline for the para-phenylenediamine sulfonic acid and then saponifying or reducing the tertiary condensation product so formed.

Example 3

94.6 parts of para-toluene sulfonic acid ester of 1:8-aminonaphthol-3:6-disulfonic acid are diazotized and combined in known manner with 27.4 parts of 1-methyl-3-aminophenyl-4-methylether. 124.2 parts of the monoazo-dyestuff so obtained are combined at 0° C. in a neutral solution with a fine aqueous suspension of 18.5 parts of cyanuric chloride. Within half an hour a solution of 2.5 parts of sodium carbonate is allowed to flow in and the temperature is then slowly raised to 40° C. where it is kept for 2 hours. The whole is then made neutral to congo with a solution of 3 parts of sodium carbonate and a neutral solution of 32 parts of dehydrothiotoluidinesulfonic acid added. The temperature is now quickly raised to 75-80° C. and in the course of it there is again allowed to flow into the mass a solution of 2.5 parts of sodium carbonate. After a further hour the formed condensation product is saponified by adding to every 1000 parts by volume of the solution 180 parts by weight of a caustic soda solution of 30 per cent. strength and keeping the temperature at 75-80° C. for one hour. The solution is then neutralized with hydrochloric acid and the dyestuff is precipitated by addition of common salt. The product thus obtained is the tertiary condensation product from 1 molecule cyanuric chloride, 2 molecules of the monoazo-dyestuff from diazotized 1:8-aminonaphthal-3:6-disulfonic acid and 1-methyl-3-aminophenyl-4-methylether, and 1 molecule dehydrothiotoluidinesulfonic acid. It corresponds very probably with the formula

It dyes cotton pure rose tints.

The same dyeing can be produced on the fibre by impregnating or dyeing the fibre with the secondary condensation product and then developing with diazobenzene.

Example 5

The diazo-compound from 13.7 parts of 2-aminobenzoic acid is allowed to flow into a solution, alkaline with sodium carbonate, of 75 parts of the secondary condensation product from 1 molecule cyanuric chloride, 1 molecule 1:8-aminonaphthal-3:6-disulfonic acid and 1 molecule dehydrothiotoluidinesulfonic acid. The dyestuff is precipitated and its separation may be completed by salting out. It corresponds very probably with the formula

and dyes cotton in strongly yellowish-red tints which are fast to light.

and dyes cotton clear rose tints, which become a light reddish violet fast to light by

treatment with copper on the fibre. The same dyeing is obtained with the dyestuff which has been previously treated with an agent yielding copper to convert it into a complex copper compound and has been then dyed on cotton.

If in the foregoing example there are substituted for the coupling component 72.7 parts of the tertiary condensation product from 1 molecule cyanuric chloride, 1 molecule 2:5-aminonaphthol-7-sulfonic acid, 1 molecule dehydrothiotoluidinesulfonic acid and 1 molecule aniline, there is obtained a dyestuff which dies cotton clear orange tints. By treatment with copper on the fibre the tine becomes reddish-brown fast to light; this is also obtained when the dyestuff is previously converted in substance into the complex copper salt and then dyed on the cotton.

Example 6

The diazo-solution from 18.8 parts of 1-oxy-2-aminobenzene-4-sulfamide is mixed cold with a neutral solution of 75 parts of the secondary condensation product, from 1 molecule cyanuric chloride, 1 molecule 1:8-aminonaphthol-3:6-disulfonic acid and 1 molecule dehydrothiotoluidinesulfonic acid. To the mixture there is added gradually the quantity of milk of lime necessary for forming the dyestuff. When coupling is complete the dyestuff is salted out. It corresponds very probably with the formula

and dyes cotton red-violet tints. By treatment with copper on the fibre or by dyeing in presence of a copper salt a reddish-violet fast to light is obtained. The dyestuff may also be converted directly into a complex copper compound, for instance, by treatment with copper sulfate; the same tints on cotton are produced by this compound.

This copper compound can also be made in the following manner:—The diazo-compound from 18.8 parts of 1-oxy-2-aminobenzene-4-sulfamide is coupled with a solution of 31.9 parts of 1:8-aminonaphthol-3:6-disulfonic acid with addition of milk of lime, the dyestuff is separated, then dissolved and converted into the complex copper salt by boiling it with a copper salt. The copper compound corresponding with 51.8 parts of dyestuff free from copper is dissolved, in the form of its neutral ammonium salt, in 1200 c. c. of hot water and the solution is mixed with a suspension of 18.5 parts of cyanuric chloride in water and much ice and the whole stirred at 0° C. for 2 hours. To the violet solution there are then added 32 parts of dehydrothiotoluidinesulfonic acid, the temperature is raised gradually to 50–60° C. and in the course of one hour a solution of 10.6 parts of sodium carbonate is run in. The dyestuff separates and is isolated by filtration. It dyes cotton in the same red-violet tints as are produced by the copper compound described above.

The corresponding dyestuff containing chromium dyes cotton violet.

Example 7

62 parts of the secondary condensation product from 1 molecule cyanuric chloride, 1 molecule 1:4-phenylenediamine-3-sulfonic acid and 1 molecule dehydrothiotoluidinesulfonic acid described in Example 2, are diazotized at 10–15° C. and coupled with a solution, alkaline with sodium carbonate, of 17.7 parts of acetoacetic anilide. When coupling is complete the whole is warmed and separation of the dyestuff is completed by addition of common salt. The dyestuff corresponds very probably with the formula

and dyes cotton clear greenish yellow tints.

Example 8

Into a neutral solution of 50 parts of the secondary condensation product from 1 molecule cyanuric chloride, 1 molecule 2:5-aminonaphthol-7-sulfonic acid and 1 molecule

mono-acetyl-1:4-phenylenediamine, and 50 parts of sodium acetate, there is caused to flow at 45° C. a diazo-compound from 32 parts of the dehydrothiolutuidine-monosulfonic acid obtainable by baking dehydrothiolutuidine sulfate. When coupling is complete, the dyestuff is salted out and isolated. It corresponds very probably with the formula

10

stuff yielding somewhat yellower dyeings on cotton.

By saponifying the dyestuff, for example, by heating it with dilute caustic soda solution, the acetyl group is eliminated; the dyestuff produced can be diazotized on the fibre and developed by β -naphthol.

The number of examples could be multiplied as desired; it suffices, however, to refer

70

75

80

20 and dyes cotton scarlet-red tints fast to light. If for the dehydrothiolutuidine sulfonic acid prescribed above are substituted 40 parts of the dehydrothiolutuidine-disulfonic acid obtainable by further sulfonation of the above-named dehydrothiolutuidine-monosulfonic acid, there is produced a similar dye-

to the numerous combinations indicated in 85 the specifications referred to in the introduction to this specification.

In the following tables the constitution and dyeing properties of a further small number of dyestuffs obtainable according to 90 the invention are given.

(106) Do	do	do	3'-aminophenyl-5-oxy-1:2-naphthimidazole-7-sulfonic acid	Bluish red bordeaux (2).
(107) Do	do	do	3'-aminophenyl-5-oxy-1:2-naphthimidazole-7-sulfonic acid	Do.
93 (108) Do	do	do	1-acetylamo-8-oxynaphthalene-3:6-disulfonic acid	Red-violet.
(109) Do	do	do	Secondary condensation product from 1 mol. cyanuric chloride, 1 mol. 1-amino-8-oxynaphthalene-3:6-disulfonic acid and 1 mol. dehydrothiotoluidinesulfonic acid.	Violet.
89 (110) 4-chloro-1:3-phenylenediamine.	do	do	Secondary condensation product from 1 mol. cyanuric chloride, 1 mol. 2-amino-5-oxynaphthalene-7-sulfonic acid and 1 mol. 1:3-phenylenediamine-4-sulfonic acid.	Red red (2).
(111) Do	do	do	Secondary condensation product from 1 mol. cyanuric chloride, 1 mol. 2-amino-5-oxynaphthalene-7-sulfonic acid and 1 mol. 1:3-phenylenediamine-4-sulfonic acid.	Do.
95 (112) 4-chloro-1:3-phenylenediamine.	Dehydrothiotoluidine-sulfonic acid	do	Secondary condensation product from 1 mol. cyanuric chloride, 2 mols. 1-amino-8-oxynaphthalene-3:6-disulfonic acid.	120
(113) 1:4-phenylenediamine-2-sulfonic acid.	Dehydrothiotoluidine-sulfonic acid	do	2-amino-1:4-diamethylbenzene, further diazotized and coupled with 2-phenyl-amino-5-oxynaphthalene-7-sulfonic acid.	Do.
90 (114) Do	do	do	2-amino-1:4-diamethylbenzene, further diazotized and coupled with 2-amino-5-oxynaphthalene-7-sulfonic acid.	Do.
(115) 1:3-phenylenediamine-4-sulfonic acid.	1:3-phenylenediamine-4-sulfonic acid	Dehydrothiotoluidine-sulfonic acid	2 mols. 2-amino-8-oxynaphthalene-6-sulfonic acid (acid coupled).	Rose.
(116) Do	do	do	2 mols. acetoacetic anilide	Greenish yellow.
(117) Do	Aniline	Aniline	3'-aminophenyl-5-oxy-1:2-naphthimidazole-7-sulfonic acid.	Red red (2).

*If dyestuff No. 26, in accordance with the data of
Example 3, has been made from the para-toluenesulfonic acid
ester of 1:8-aminonaphthol-3:6-disulfonic acid, the
last chlorine atom of the cyanuric ring is then replaced by
an OH-group.

The numbers which follow some of the colors of the dyeings in the above table have the following significance:—

5 (1) After-treatment with copper or dyeing in the form of copper salt.

(2) Diazotizing on the fibre and developing with β -naphthol.

(3) Diazotizing on the fibre and developing with phenylmethylpyrazolone.

10 (4) Developing on the fibre with 4-nitro-diazobenzene.

It is clear that other amino- and oxy-thiazoles not named in the foregoing tables or examples, may be used. Such are described in literature, for example in British specifications Nos. 406 of 1894, and 3026 of 1894 and in German specifications Nos. 79,093, 81,711, 83,089, 97,285, 98,813, 277,395.

What we claim is:—

20 1. A process for the manufacture of new direct dyeing azo-dyestuffs containing at least one thiazole ring and at least one cyanuric ring, consisting in causing diazotized diazotization components of the benzene or naphthalene series to react on coupling components, these components being so selected

diazotization components of the benzene or naphthalene series to react in ortho-position to the OH-group on such coupling components of the general formula

70

75

wherein x stands for halogen or a residue which can replace halogen, and wherein the naphthalene nucleus and the benzothiazole complex each contains at least one sulfo group.

4. A process for the manufacture of new direct dyeing azo-dyestuffs containing at least one thiazole ring and at least one cyanuric ring, consisting in causing diazotized diazotization components of the benzene or naphthalene series to react in ortho-position to the OH-group on such coupling components of the general formula

85

95

100

30

35

40 that at least one component contains at least one thiazole ring and at least one component contains at least one cyanuric ring.

45 2. A process for the manufacture of new direct dyeing azo-dyestuffs containing at least one thiazole ring and at least one cyanuric ring, consisting in causing diazotized diazotization components of the benzene or naphthalene series to react on such coupling components of the naphthalene series which contain at least one thiazole ring and at least 50 one cyanuric ring.

wherein x stands for halogen or a residue which can replace halogen, and wherein one of the y 's stands for an H atom and the other y for an SO_3H group.

5. A process for the manufacture of new direct dyeing azo-dyestuffs containing at least one thiazole ring and at least one cyanuric ring, consisting in causing diazotized mononuclear diazotization components of the benzene or naphthalene series to react in ortho-position to the OH-group on such coupling components of the general formula

110

115

55

60

3. A process for the manufacture of new direct dyeing azo-dyestuffs containing at least one thiazole ring and at least one cyanuric ring, consisting in causing diazotized

120

125

wherein x stands for halogen or a residue which can replace halogen, and wherein one of the y 's stands for an H atom and the other y for an SO_3H group.

130

6. A process for the manufacture of new direct dyeing azo-dyestuffs containing at least one thiazole ring and at least one cyanuric ring, consisting in causing diazotized diazotization components of the benzene or naphthalene series containing an azo-chromophor to react in ortho-position to the OH-group on such coupling components of the general formula

10

wherein x stands for halogen or a residue dyestuffs of the general formula

20

which can replace halogen, and wherein one of the y 's stands for an H atom and the other y for an SO_3H group.

7. As new products the direct dyeing azo-dyestuffs deriving from diazotizing components of the benzene or naphthalene series characterized by the simultaneous presence in their molecule of at least one cyanuric ring and at least one thiazole ring, which products form powders more or less intensively colored, dissolving in water to solutions of all

40

colors of the spectrum and of those which are obtained by combination of the said colors, and dyeing the textile fibre from cellulose similar tints.

8. As new products the direct dyeing azo-dyestuffs deriving from diazotizing components of the benzene or naphthalene series and from such coupling components which contain in their molecule simultaneously at least one cyanuric ring and at least one thiazole ring, which products form powders more or less intensively colored, dissolving in water to solutions of all colors of the spectrum and of those which are obtained by combination of the said colors, and dyeing the textile fibre from cellulose similar tints.

9. As new products the direct dyeing azo-dyestuffs deriving from diazotizing compo-

nents of the benzene or naphthalene series and from such coupling components which contain in their molecule simultaneously one naphthalene nucleus, one cyanuric ring and one thiazole ring, which products form dark 70 powders, dissolving in water to red, violet, blue or green solutions, and dyeing cotton similar tints.

10. As new products the direct dyeing azo-

75

dyestuffs of the general formula

20

wherein R stands for the residue of any diazotization component of the benzene or naphthalene series, x stands for halogen or a residue which can replace halogen, and wherein one of the y 's stands for an H atom and the other y for an SO_3H group, which products form dark powders, dissolving in water to red, violet, blue or green solutions, and dyeing cotton similar tints.

11. As new products the direct dyeing azo-dyestuffs of the general formula

40

wherein R stands for the residue of such a diazotization component of the benzene or naphthalene series which contains an azo-chromophor, x stands for halogen or a residue which can replace halogen, and wherein one of the y 's stands for an H atom, and the other y for an SO_3H group, which products form dark powders, dissolving in water to 115 violet, blue or green solutions, and dyeing cotton similar tints.

In witness whereof we have hereunto signed our names this 3rd day of October 1928.

125

JOSEPH GYR.
OTTO KAISER.
